(57) **CLAIM**

The ornamental design for a watchcase, as shown and described.

DESCRIPTION

FIG. 1 is an enlarged perspective view of a watchcase showing our new design;

FIG. 2 is a front elevational view thereof;

FIG. 3 is a left side elevational view thereof;

FIG. 4 is a right side elevational view thereof;

FIG. 5 is a rear elevational view thereof; and,

FIG. 6 is a top plan view thereof; the bottom plan view is a

mirror image of the top plan view thereof.

The broken lines are for illustrative purposes only and form

no part of the claimed design.
